(57) **CLAIM**

The ornamental design for the fishing lure, as shown and described.

DESCRIPTION

FIG. 1 is a perspective view of the fishing lure, three dimensional form;

FIG. 2 is another perspective view of the fishing lure of FIG. 1;

FIG. 3 is a right side view of the fishing lure of FIG. 1;

FIG. 4 is a left side view of the fishing lure of FIG. 1;

FIG. 5 is a top view of the fishing lure of FIG. 1;

FIG. 6 is a bottom view of the fishing lure of FIG. 1;

FIG. 7 is a front side view of the fishing lure of FIG. 1; and,

FIG. 8 is a rear side view of the fishing lure of FIG. 1.

The broken line showing of environment in the drawings is included for the purpose of illustrating only and forms no part of the claimed design.
